UNITED STATES PATENT OFFICE.

GUSTAV EGLOFF AND HARRY P. BENNER, OF CHICAGO, ILLINOIS, ASSIGNORS TO
UNIVERSAL OIL PRODUCTS COMPANY, OF CHICAGO, ILLINOIS, A CORPORATION OF
SOUTH DAKOTA.

PROCESS AND APPARATUS FOR TREATING OIL.

Application filed October 23, 1920, Serial No. 419,058. Renewed October 26, 1923.

To all whom it may concern:

Be it known that we, GUSTAV EGLOFF and HARRY P. BENNER, both citizens of the United States, residing in the city of Chicago, county of Cook, and State of Illinois, have invented certain new and useful Improvements in Processes and Apparatus for Treating Oil, of which the following is a specification.

10 This invention relates to improvements in process and apparatus for treating oil and refers more specifically to the cracking of petroleum oils having a higher carbon content than most oils so as to produce pure carbon for use in various arts such as pigments, tires, phonograph records, electrodes, deodorizing and decolorizing of oils, etc.

In carrying out the process, the petroleum oil treated is cracked by heat and pressure 20 and the carbon precipitated is continuously conveyed to a filter press and thence subjected to the action of suitable solvents.

In the cracking of petroleum oils, the production of carbon is an inevitable necessity but a nuisance and the carbon is generally either a more or less waste product or suitable only for very cheap uses. By means of the present invention, however, we continuously remove the carbon from the system which in itself is advantageous and then as a feature of the invention, continuously subject it, first, to filtering action and then to the action of solvents.

We also provide a novel apparatus for carrying out our process. In the drawing, the single figure is a view partly in side elevation and partly in section, of our improved apparatus.

Referring more in detail to the drawing, 10 designates a furnace, 2 the burner, 3 the combustion chamber or fire zone and 4 the stack. In the furnace is mounted the still, which may be of any suitable type. In the present instance, we have shown a continuous coil of pipe as for example, a 4" coil 5, the inlet side of which is connected to inlet line 6 having throttle valve 7 and leading to charging pump 8. The inlet side of the charging pump 8 is connected by a line 9 having 50 throttle valve 10, to any suitable supply tank. The heated oil while in liquid phase is delivered to an expansion chamber 11 by means of transfer line 12 in which is interposed a throttle valve 13. This expansion

chamber is provided with drawoff line 14 55 having a throttle valve 15. At its upper end it is provided with vapor outlet pipe 16, having throttle valve 17 and this pipe 16 extends into the lower end of a dephlegmator 18.

A spaced cap member 19 is provided above the upper end of the pipe 16 to prevent the reflux condensate from falling back into the expansion chamber while at the same time permitting the vapors to pass 60 freely into the dephlegmator. The dephlegmator is provided with suitable baffles 20 and 21 and at its upper end with a vapor outlet pipe 22, having throttle valve 23, which pipe 22 leads to condenser coil 24 70 seated in condenser box 25. The coil 24 is connected by means of pipe 26 having throttle valve 27 to the upper end of a receiver 28. This receiver 28 is provided with pressure gauge 29, liquid level gauge 30, gas outlet pipe 31, having throttle valve 32 and liquid drawoff pipe 33, having throttle valve 34. Reflux condensate is drawn off from near the lower end of the dephlegmator by pipe 35 having throttle valve 36 and leading to a 80 cooling coil 37 seated in box 38. The coil 37 is connected by pipe 39 having throttle valve 40, to the upper end of receiver 41. This receiver 41 is provided with pressure gauge 42, liquid level gauge 43, gas outlet pipe 44, 85 having throttle valve 45 and liquid drawoff pipe 46 having throttle valve 47. The arrangement is such that the reflux condensate may be separately cooled and collected and either returned to the supply tank containing 90 the charging oil and thus again retreated or it may be retreated elsewhere.

Referring now to the means for filtering and treating the carbon precipitated in the expansion chamber, at the lower end of the latter, we provide a drawoff pipe 48 having valve 49 and connected to suction pump 50. The discharge side of this suction pump 50 is connected by line 51 having throttle valve 52 to a filter press 53. The heavy oil and suspended carbon therein is pumped out of the expansion chamber by means of the pump 50 into the filter press 53 where the oil is pressed out. The carbon, substantially free from its oil, is delivered to trough 54 and thence to the carbon buckets 55 carried by the traveling conveyor 56. These buckets deliver the carbon into the upper end of

an extraction tank 57, this tank having an inlet throat 58 to receive the carbon. The tank is provided with a vertically extending shaft 59 rotated in any suitable manner, which shaft carries agitator blades 60. A solvent is continuously circulated through the tank by means of the circulating pump 61 and lines 62 and 63 and 64, and feed line 65. Throttle valves 66 and 67 are also provided as shown. The solvent used by us may be benzine carbon bisulphide or the extractives. The purified carbon may be withdrawn from the tank when the operation is finished. The agitator blades serve to circulate the solvent through and around the carbonaceous material.

The process may be operated as follows: A Mexican or California petroleum oil, particularly one which will produce carbon as high as 20 to 30% of the oil by weight cracked may be fed through the heating coil and there heated to a temperature of 700 degs. F. and maintained under a pressure of say, 100 pounds by suitably regulating the valve 13. The heated oil as it passes into the expansion chamber vaporizes and carbon is precipitated. The pressure on the balance of the system may be reduced to atmospheric or to a pressure of 75 pounds or if desired, a uniform pressure may be maintained on the entire system. The heavy residue with its carbon content is continuously drawn off by the pump 50 and forced into the filter press where the oil constituents thereof are pressed out, drawn off and saved. The carbon content is continuously delivered to the extraction tank and there purified to produce pure carbon. This pure carbon is suitable for the purposes hereinbefore referred to as well as for any other purpose which pure carbon is suitable for.

We claim as our invention:

1. In an apparatus for treating petroleum

oil, the combination with a still in which the oil may be subjected to a cracking temperature and pressure, an expansion chamber connected thereto, a filter press, means for drawing off the carbon containing residue from the expansion chamber and forcing it through the filter press, an extraction tank for receiving the carbon from the filter press, means for circulating a solvent through the extraction tank, and means for agitating the contents of the extraction tank.

2. In an apparatus for treating petroleum oil, the combination with a still in which the oil may be subjected to a cracking temperature and pressure, an expansion chamber connected thereto, a filter press, means for drawing off the carbon containing residue from the expansion chamber and forcing it through the filter press, means for circulating a solvent through an extraction tank provided for receiving the carbon from the filter press.

3. In an apparatus for treating petroleum oil, the combination with a still in which the oil may be subjected to a cracking temperature and pressure, an expansion chamber connected thereto, a filter press, means for drawing off the carbon containing residue from the expansion chamber and forcing it through the filter press, an extraction tank for receiving the carbon from the filter press, and means for agitating the contents of the extraction tank.

4. A process of producing purified carbon consisting in cracking petroleum oil, precipitating the carbon thereby produced, withdrawing the carbon containing oil, passing it through a filter, removing the carbon from the filter and subjecting it to the action of solvents.

GUSTAV EGLOFF.
HARRY P. BENNER.
